FRANK S. STEVENS, OF READING, PENNSYLVANIA.

BASE-SUPPORTED RAIL-JOINT.

1,145,335.

Specification of Letters Patent.

Patented July 6, 1915.

Application filed April 6, 1914. Serial No. 829,844.

To all whom it may concern:

Be it known that I, FRANK S. STEVENS, a citizen of the United States, and a resident of Reading, in the county of Berks and State of Pennsylvania, have made and invented certain new and useful Improvements in Base-Supported Rail-Joints, of which the following is a specification.

My invention relates to rail joints, my more particular purpose being to produce an improved device of this character in which special provision is made for supporting the ends of the rails at the points where the greatest stresses are likely to occur.

More particularly stated, in making my improved rail joint, I employ a pair of splice bars each resting upon suitable supports and provided with a depending portion carrying a massive seat, the latter being so located relatively to the rails as to support the ends thereof directly, and otherwise to resist the greatest strains received from the rails—the splice bar being of such form that it is preferably made, in practice, from cast metal.

My invention further contemplates the use of bolts whenever desired, for extending through the depending portions of the splice bars and thus preventing the splice bars and parts connected therewith from spreading apart in consequence of the downward pressure exerted by the rails.

My invention also embraces various forms and combinations of parts, used for the purpose of supporting the rails, and particularly the ends thereof, upon a bridge-like structure of exceptional strength.

In addition, my invention covers various improvements in rail joints, for increasing the general efficiency thereof.

As my device may be practised in different ways, I will for the sake of conciseness describe only two forms, and these may be considered as merely representative of the invention.

Reference is made to the accompanying drawing forming a part of this specification, and in which like letters indicate like parts.

Figure 1 is a side view, partly in elevation and partly broken away, showing my improved form of rail joint. Fig. 2 is a section, on the line 2—2 of Fig. 1, looking in the direction of the arrow. Fig. 3 is a detail view showing in fragmentary elevation the inner face of the depending portion

of one of the splice bars. Fig. 4 is a section corresponding to Fig. 2, but showing a different form of seat for engaging and supporting the lower portion of the rail.

The rail heads are shown at 5, the rail webs at 6, and the rail feet at 7. Located below the rail feet 7 are flat supporting plates 8, resting upon cross ties 9. A pair of splice bars are shown at 10, and are each provided with a thickened portion 11, located at the middle of the bar, reckoning in the general direction of the length thereof—this thickened portion spanning directly across the abutting ends of the rails. Bolts 12 extend through the thickened portions 11 of the splice bars and also through the webs 6—suitable holes being formed in these parts for this purpose. Two of these holes, immediately adjacent the rail ends, are made slightly elliptical, as indicated at 12^a in Fig. 1, in order to allow a slight degree of play between the rail ends and the splice bars, at points adjacent the middle portions 80 of the splice bars.

Nuts 13 are fitted upon the bolts 12. Each splice bar 10 is provided with a depending portion 13^a, having a bead 14 integral with it and following its inner peripheral surface, as may be understood from Figs. 1 and 3. Two bolts 15, somewhat longer than the bolts 12, extend through holes in the depending portions 13^a, and are fitted with nuts 16. Each depending portion 13^a is provided with a massive seat 17 integral with it and of suitable proportions to withstand a very severe strain, either downward or horizontal, as the case may be.

A base plate is shown at 18, and is loose relatively to the seats 17 upon which it rests directly. The base plate 18 is provided with a centrally disposed rib 19 integral with it and extending parallel with the rails. This strengthening rib thus acts as a brace for the base plate 18, in the direction in which said base plate is subjected to the greatest strains, from the rail ends resting upon it. The rib 19 is provided with sloping ends 20, of the form indicated in Fig. 1, so that the rib extends well down in between these bolts, and is unable to move out of position because directly obstructed by the presence of the bolts. The splice bars 10 are provided further with notches 21 or slots, and by aid of the latter fastenings 22 are placed in position for holding the splice bars down upon the supporting plates 8.

In assembling the parts, I find it conven-

ient to first place one of the splice bars 10 in position, bringing it well up against the rails. The base plate is next inserted, a portion of the base plate extending outwardly over the adjacent seat 17 of the splice bar. The other splice bar is next placed in position, its seat 17 being brought under, and in engagement with, the adjacent portion of the rail feet 7. The bolts 12 and nuts 13 are next fitted in position and drawn tight. Next the bolts 15 are extended through the depending portions of the splice bars, and tightened by the nuts 16. This being done, the base plate 18 is forced upwardly against the underside of the rail feet 7, so that when the joint receives the load, the bolts 15 effectively prevent the splice bars, and particularly the lower or depending portions thereof, from spreading apart. This arrangement protects the joint at its weakest parts. That is to say, the thickened portions 11 strengthen the joint where it would otherwise be weak on account of the weakness of the web 6, and the massive seats 17, by pressing upwardly against the rail seat 8, effectively produce an upwardly-directed initial strain which meets the downward strain, which may be thrown upon them afterward in consequence of the load. In some instances, as indicated in Fig. 4, I may discard the base plate 18. For this purpose, I make the splice bars 23 of the form here indicated in cross section, and provide each splice bar with a massive portion 24 integral with it and serving as a rail seat. This rail seat is flat on top, and engages directly the lower surface of the rail seat 7. The other parts of the splice bars, and parts immediately associated therewith, are formed and used as above described.

With the form shown in Fig. 4, and in some instances even with the form disclosed in Figs. 1, 2 and 3, the bolts 15 may be omitted if desired. In this event, the splice bars are held together merely by the bolts 12.

It will be also understood, without further description or illustration, that the device above described is applicable to both straight and compromise joints, that is, is applicable for connecting rails of the same weight as well as those of different weight.

I do not limit myself to the precise construction shown, as variations may be made therein without departing from the spirit of the invention, the scope of which is commensurate with my claims.

Having thus described my invention, what I claim as new and desire to secure by Letters Patent is as follows:

60 1. In a rail joint the combination of a pair of splice bars provided with thickened

middle portions and with depending portions having seats disposed adjacent said thickened portions, bolts extending through said depending portions, and a base plate 65 resting loosely upon said seats and provided with a depending web extending in the direction of the length of said splice bars, said web also extending between said bolts and having a total length less than the distance 70 between said bolts.

2. In a rail joint the combination of a pair of splice bars provided with depending portions having seats, bolts extending through said splice bars and disposed adjacent the ends of said seats, and a base plate 75 resting upon said seats and provided with a depending portion having a length less than the space between said bolts, said depending portion extending loosely between 80 said bolts in order to prevent said base plate from creeping in the direction of the length of said splice bars.

3. In a rail joint the combination of a pair of splice bars, each provided with a 85 thickened portion, and with a depending portion disposed adjacent the said thickened portion, bolts extending through the depending portions of the splice bars and disposed parallel to each other, and a base 90 plate supported by said depending portions and provided with a depending portion having a length less than the distance between the bolts, said depending portion of said base plate extending loosely between said 95 bolts in order to limit the play of said base plate in the general direction of the length of said splice bars.

4. A rail joint comprising a pair of splice bars, means for securing the same to the 100 meeting ends of a rail, each splice bar provided with a depending central portion, said depending central portion provided with a longitudinally extending laterally projecting ledge defining a seat for the rail flange, 105 and a base plate resting upon said ledge and supporting said rail flange, said base plate provided with a depending web extending in the direction of the length of said splice bars, and fastening means extending between the depending portions of 110 said splice bar and located in front and in the rear of said web preventing the longitudinal creeping of said base plate.

Signed at Reading, in the county of 115 Berks and State of Pennsylvania, this third day of April, A. D. 1914.

FRANK S. STEVENS.
